CHANGE MAKER

William S. Bennett, Lakewood, Ohio, assignor to National Rejectors, Inc., St. Louis, Mo., a corporation of Missouri

Filed June 16, 1960, Ser. No. 60,984

Term of patent 14 years

(Cl. D52—4)

FIG. 1

FIG. 2

Fig. 1 is a perspective view of a change maker embodying my new design, and

Fig. 2 is a side elevational view thereof.

The undisclosed side of the change maker is substantially the same in appearance as the side shown and the back is plain. The essential features of the design reside in the portions shown in solid lines.

I claim:

The ornamental design for a change maker, as shown and described.
